[57] CLAIM

The ornamental design for a combined magnetic door stop and striking plate, substantially as shown and described.

DESCRIPTION

FIG. 1 is a perspective view of a combined magnetic door stop and striking plate showing my new design;
FIG. 2 is a front view of the magnetic door stop, shown separately for ease of illustration;

FIG. 3 is a rear view of FIG. 2;

FIG. 4 is a side view taken from the right of FIG. 2, the side opposite being a mirror image thereof;

FIG. 5 is a top view of FIG. 2;

FIG. 6 is a bottom view of FIG. 2;

FIG. 7 is a front view of the striking plate, again shown separately for clarity of illustration;

FIG. 8 is a rear view of FIG. 7;

FIG. 9 is a side view taken from the right of FIG. 7, the side opposite being a mirror image thereof;

FIG. 10 is a top view of FIG. 7, the bottom being a mirror image thereof.
